INFLATABLE FABRIC SEGMENT OF CURVED CONFIGURATION

Charles J. Ford, Akron, Ohio, assignor to Wingfoot Corporation, Akron, Ohio, a corporation of Delaware

Application October 28, 1950, Serial No. 192,721

7 Claims. (Cl. 139—410)

1

The present invention pertains to an inflatable fabric segment or structural element. More particularly, the invention is concerned with a form of inflatable structure made entirely from fabric which has been coated or treated to render it impervious to gas and which is capable of assuming a curved configuration upon inflation.

For certain specific uses of more or less temporary nature, structures fabricated from waterproofed canvas or rubberized fabrics and having the ability to be quickly and easily constructed and dismantled have proven highly advantageous. Such conventional structures, however, usually require some means by which the canvas or fabric is suspended or supported in the form which it is to assume, depending upon the use to which it is put. These supports are usually rigid and often quite bulky, as a result of which they are exceedingly difficult to handle, store, and transport. In addition, such supporting or suspension means present obstructions whether disposed interiorly or exteriorly of the structure when constructed.

The present invention contemplates a form of structural element which will incorporate not only the framework or supporting structure, but also the confining walls as well in a single unit. This novel construction provides a structural member which eliminates virtually all of the problems encountered in the aforementioned conventional structures. Moreover, the product of the present invention possesses the features of rigidity and ease of storage and erection not found in the ordinary forms of structure.

There are many places where not only avoidance of rigid supporting means is desirable, but also curved or cylindrical surfaces can be employed to better advantage than flat or planar surfaces which must necessarily be angularly joined together to form most structures. The curved configuration of the fabric segment or structural element disclosed herein is highly advantageous in avoiding sharp or angular joints. The curved configuration of the fabric segment moreover affords a highly advantageous structural shape which possesses greater strength characteristics.

Thus, it is an object of the present invention to provide a form of inflatable fabric segment or structural element which possesses the aforementioned attributes by reason of its ability to assume a curved configuration upon inflation.

Other objects and advantages of the product of the invention will become apparent as a detailed description of one embodiment of the invention proceeds.

2

Figure 1 of the drawings represents a vertical cross-section through an inflated flat fabric segment illustrating a form of conventional structural element. Figure 2 illustrates a vertical section through a typical curved fabric segment embodying the teachings of the present invention. Figure 3 is an enlarged fragmentary section corresponding generally to that shown in Figure 2. Figure 4 is a fragmentary plan view of a portion of the fabric segment shown in Figure 3 as seen from the line 4—4 therein. Figure 5 is an enlarged section of a portion of the fabric taken along the line 5—5 in Figure 4. Figure 6 illustrates a typical rubber cored thread such as may be used in the fabric employed in the construction of the fabric segment. Fig. 7 is a perspective view with a portion broken away.

In Figure 1 of the drawings is shown one form of fabric segment, indicated generally by the reference numeral 1, constructed from two spaced plies of fabric 2 and 3 which are joined together in the weaving operation by means of a plurality of drop or tie-threads 4. The fabric segment 1 is conveniently formed into an envelope by joining the ends or edges of the fabric plies 2 and 3 as by means of the tapes 5 and 6 which are securely cemented in place about the entire periphery of the fabric segment 1.

The outer or exposed surfaces of the fabric plies 2 and 3 are customarily coated with some suitable gas-impervious coating such, for example, as natural or synthetic rubber and the like. The tapes 5 and 6 which cooperate with the fabric plies 2 and 3 to form an envelope are made from a fabric which has previously been coated with rubber or impregnated with a material which will serve to retain gas under pressure in the chamber 7 of the fabric segment 1. Although many other coating and impregnating materials are known and could be used for the purpose of rendering the fabric impervious to gas under pressure, the coating which possesses all the desired characteristics and has been chiefly employed is rubber and may be of either natural or synthetic origin. Any suitable form of inflating tube or valve 8 may be provided.

For many purposes, the flat form of fabric segment 1 has many disadvantages as we have already seen. To overcome these disadvantages, the fabric segment 8 of Figures 2 and 7 comprising a top fabric ply 9 and a bottom fabric ply 10 has been devised. The fabric segment 8 allows for extensibility of the top ply 9 along the larger radius of the curved section and is characterized by a smoothly curved configuration upon inflation with the degree or extent of curvature being

readily controllable. Heretofore, in order to produce a curvature in a flat fabric segment such as the segment 1, it has been the practice to take a series of folds or tucks in the fabric ply 3 along the smaller radius of the desired curved section. Such folding or tucking creates a break line in the fabric segment 1, tending to weaken it, and frequently interferes with the freedom of the tie threads 4 and, as a result, does not produce a satisfactorily smooth curved section.

The extensibility of the top ply 9 of the fabric segment, as will be seen from Figure 5 of the drawings, is achieved by the use of threads 14 which are capable of limited stretch disposed in the fabric in the direction of curvature. This property may be imparted to the threads 11 in any of several different ways. One of the common types of stretchable thread which may be employed to advantage is that illustrated in Figures 5 and 6 in which a rubber core 12 is covered with a spirally wrapped fiber 13 of cotton, rayon, nylon, or the like. The rubber core 12 provides the desired extensibility, while the fiber wrap 13 serves to limit somewhat the extent of stretch of the thread 11.

The threads 14 in the fabric forming the top ply and extending transversely of the extensible rubber cored threads 11 are ordinary threads of cotton, rayon, nylon, or the like usually corresponding to the fiber wrap 13 on the rubber cored thread for the sake of uniformity. These threads 14 and the drop or tie threads 15 which serve in the same manner as their counterparts 4 in the fabric segment 1 of Fig. 1 to join together the top and bottom plies 9 and 10 of the fabric segment 8, are substantially inextensible. The two-ply fabric with connecting tie threads woven at least partially in each ply is similar in construction to uncut pile fabrics.

As previously indicated, the top and bottom fabric plies 9 and 10 are covered with a coating 16 and 17, respectively, of rubber or the like. Next, the top and bottom plies 9 and 10 of coated fabric are joined as shown in Fig. 2 by means of the fabric tapes 18 and 19 which are of rubberized fabric and adhesively bonded to the fabric plies adjacent their edges, thereby forming an envelope which encloses a gas confining chamber 20 capable of inflation as by means of the inflating tube or valve 22. On subsequent admission of gas to the chamber 20, the top ply of fabric 9, being capable of extension, will stretch, and the tie threads 15 and the composition of the bottom fabric ply 10, by reason of their being inextensible, will cause the fabric segment 8 to assume the curved configuration illustrated in Figure 2.

Whenever the gas is released from the chamber 20, the fabric segment 8 will flatten out, but will always be capable of assuming the predetermined degree of curvature on subsequent inflation. This curved structure is capable of extensive use in all types of temporary buildings, shelters, forms, flotation elements, supporting structures, and the like.

While certain representative embodiments and details have been shown for the purpose of illustrating the invention, it will be apparent to those skilled in this art that various changes and modifications may be made therein without departing from the spirit or scope of the invention.

I claim:

1. An inflatable fabric segment capable of assuming a curved configuration upon inflation, said fabric segment comprising a first ply of

material which is capable of being stretched in one of its dimensions; a second ply of substantially inextensible material; a plurality of ties anchored to each of the plies for retaining them in predetermined spaced relation, said plies being sealed at their margins to form an envelope; and a gas-impervious coating on the exposed surfaces of each ply.

2. An inflatable fabric segment capable of assuming a curved configuration upon inflation, said fabric segment comprising a first ply of woven fabric which is extensible in one of its dimensions; a second ply of woven fabric which is substantially inextensible; a plurality of individual tie threads woven partially in each of the plies so disposed that the fabric plies are capable of being arranged in spaced, generally parallel relation to each other; means for sealing the marginal edges of the juxtaposed plies; and a vulcanized rubber coating on the exposed surfaces of the fabric plies.

3. An inflatable fabric segment capable of assuming a curved configuration upon inflation, said fabric segment comprising a first ply of fabric embodying in its construction threads which are extensible disposed in one direction in said fabric; a second ply of fabric woven from threads which are substantially inextensibly spaced from the first ply, but attached thereto by means of a plurality of tie threads woven partially into each of the fabric plies, the marginal edges of said plies being joined to form an envelope; and a gas-impervious coating on the outermost surfaces of each ply.

4. An inflatable fabric segment capable of assuming a curved configuration upon inflation, said fabric segment comprising two fabric plies, one of which embodies in its construction threads capable of limited extensibility extending in one direction therein, said plies being joined together by a plurality of tie threads woven partially into each of the fabric plies; means joining the marginal edges of the plies in the form of an envelope; and a thin coating of rubber compound vulcanized on those faces of the plies which are opposed to those into which the tie threads are woven.

5. An inflatable fabric segment capable of assuming a curved configuration upon inflation, said fabric segment comprising two fabric plies, one of which embodies in its construction threads capable of limited extensibility extending in one direction therein, said plies being sealed at their marginal edges and joined together in spaced, mutually parallel relation by a plurality of substantially inextensible tie threads woven partially into each of the fabric plies; and a thin coating of rubber compound vulcanized on those faces of the plies which are opposed to those into which the tie threads are woven.

6. An inflatable fabric segment capable of assuming a curved configuration upon inflation, said fabric segment comprising two fabric plies, one of which embodies in its construction rubber cored threads which provide limited extensibility of the fabric in one of its dimensions, said plies being sealed together adjacent the margins thereof in the form of an envelope and joined together by a plurality of the inextensible threads woven partially into each of the fabric plies so as to permit the same to be spaced apart; an inflating tube in one of the plies; and a rubber coating on the surface of each ply opposite that in which the tie threads are anchored.

7. An inflatable fabric segment capable of as-

suming a curved configuration upon inflation, said fabric segment comprising a first fabric ply embodying in its construction threads having a fiber wrapped rubber core extending in one direction therein to render the ply extensible; a second fabric ply of substantially inextensible construction; a plurality of tie threads woven partially in each of the fabric plies in such fashion that the plies are capable of being spaced apart from each other in mutually parallel relation; means sealing the marginal edges of the fabric plies to form an envelope; an inflating tube in one of the plies; and a vulcanized rubber coating on the exposed surface of each ply.

CHARLES J. FORD.
